C. R. SHORT ET AL

INTERNAL COMBUSTION ENGINE

Filed Dec. 1, 1921

UNITED STATES PATENT OFFICE.

CHARLES R. SHORT, OF DAYTON, OHIO, AND ALEX TAUB, OF DETROIT, MICHIGAN, AS
SIGNORS TO GENERAL MOTORS CORPORATION, OF DETROIT, MICHIGAN, A COR-
PORATION OF DELAWARE.

INTERNAL-COMBUSTION ENGINE.

Application filed December 1, 1921. Serial No. 519,215.

To all whom it may concern:

Be it known that we, CHARLES R. SHORT, a subject of the King of Great Britain, and ALEX TAUB, a citizen of the United States, 5 and residents of Dayton, county of Montgomery, State of Ohio, and Detroit, county of Wayne, State of Michigan, respectively, have invented certain new and useful Improvements in Internal-Combustion Engines, 10 of which the following is a full, clear, concise, and exact description, such as will enable others skilled in the art to which the invention relates to make and use the same, reference being made therein to the accompanying drawings, which form a part 15 of this specification.

Our invention relates to internal combustion engines of the heavy oil type wherein a liquid hydrocarbon fuel is supplied to the 20 working cylinder of the engine in the liquid form and unmixed with air in an amount sufficient to accomplish the burning thereof (although in such engines a little air is frequently introduced into the cylinder 25 along with the fuel), the air necessary to the burning of the fuel being present in the working cylinder before the fuel enters thereinto.

The principal object of our invention is 30 to provide various improvements in and relating to engines of the type or class above referred to, and particularly to the means concerned with the supplying of the liquid fuel to the engine; the result being 35 an engine which is simple in construction and one in which the quantities of fuel supplied upon each working stroke may be varied in accordance with the work done by the engine.

40 Further objects of our invention will appear from the following description which, in connection with the accompanying drawing, constitutes a disclosure and specification of the best form of our invention at present known to us; it being appreciated, however, that our invention includes all such variations and modifications of the particular embodiment thereof thus disclosed as come within the scope of the concluding claims, wherein the distinguishing features of our invention are particularly pointed out.

In the drawing:

Figure 1 is a sectional view showing our

improved engine, the crank shaft and other 55 elements of common and well known form being omitted as unnecessary to an understanding thereof,

Figure 2 is a similar sectional view showing the fuel supply mechanism alone, and 60 in another position and upon a larger scale.

Figure 3 is a view showing certain features of the fuel supplying mechanism.

Figure 4 is a view showing means for varying the time relative to the cycle of operation of the engine at which fuel is supplied thereto, in side elevation.

Figure 5 is a sectional view taken upon an inclined plane indicated by the line 5—5, Figure 2.

70 Referring now to the drawing, the reference numeral 5 designates the working cylinder of the engine which is full of air at the beginning of the compression or up stroke of the piston 6; such air being 75 introduced into the cylinder by a distinct suction stroke of the piston as in engines operating upon a four-stroke cycle, by a separate pump in two-stroke cycle engines, or otherwise; our invention being independent 80 of cycle so long as there is air present in the cylinder which is compressed during the compression stroke of the engine. The cylinder is shown as provided with a head 7 which carries an exhaust valve 8 operated 85 by a rocker 9 and push rod 10 from a cam shaft 11; although our invention is not concerned with the valve mechanism of the engine, which may be of any suitable type and form.

90 Formed within the head 7 is a cylinder 12 within which the piston 13 of a fuel supply pump operates, said cylinder having a supply port 14 leading thereinto, and a discharge port 15 leading therefrom and 95 into the working cylinder; this latter port being controlled by a combined cylinder head and valve 16 which is held to the left by a spring 17 the force of which is overcome by the pressure within the cylinder 12 as the piston 13 moves toward the right; the port in question being opened and the fuel forced into the working cylinder when the pressure becomes sufficient to counteract the force of the spring, as will be understood. We intend that this spring 17 shall be variable as to tension, as by providing an adjustable abutment for the outer end

thereof to rest against; although this, being an obvious expedient, is not shown in detail.

The fuel pump piston 13 is operated from a cam 18 upon the cam shaft 11 through a lever 19 the outer end of which is adjustably supported as by means of an eccentric 20 which is angularly adjustable, and the inner end of which acts upward upon a push rod 21 held down by a spring 22; a suitable roller being commonly provided for the cam to act against, as shown. The upper end of this push rod is pivotally connected at 23 with two toggle links 24, 25 the former of which is pivotally connected with the said piston 13, and the latter of which is pivotally connected at 26 with a fixed bracket and has an extension or toe 27 which operates the plunger 28 of a fuel measuring device to be next described.

Formed also in the cylinder head and extending parallel with the fuel pump cylinder is a passage within which the sleeve 29 is located, and within which sleeve the plunger 28 operates; the sleeve being provided with a side opening at 30 which is always in communication with a port 31 through which fuel is supplied by a pipe 32, and with an outlet port 33 through which fuel passes into a fuel chamber 34 between the right hand end of the sleeve 29 and the adjacent end wall of the passage within which said sleeve is placed. Within the sleeve 29 is a cylindrical measuring chamber 35; and the right-hand end 36 of the plunger 28 enters this chamber when the parts are in one position as shown in Figure 2 to expel liquid fuel therefrom through the port 33 and into the fuel chamber 34, and moves out of said chamber when the parts are in another position as shown in Figure 1 to permit the same to fill with fuel supplied through the pipe 32, port 31 and opening 30. The plunger 28 is pushed to the right by the inward swinging of the toe 27, and is urged toward the left by a spring 37 acting thereupon, as will be understood.

The sleeve 29 is adjustable in the direction of its length to thereby vary the extent to which the measuring chamber 35 is entered by the end 36 of the plunger 28, the stroke of which is constant, whereby the amount of liquid fuel supplied to the fuel chamber 34 each stroke of said plunger 28 may be varied; said adjusting means being shown as comprising an angularly adjustable cam member 38 carried by said sleeve and acting upon a similar cam 39 at the end thereof, and which cam is provided with an arm whereby it may be operated manually or by suitable governor mechanism; the particular form of adjusting mechanism employed, however, being a matter not primarily involved in this present application.

65 The reference numeral 40 designates a

passage whereby and through which the fuel chamber 34 is placed in communication with the interior of the working cylinder; said passage including as a part thereof a recess or groove 41 provided in the exterior surface of the fuel pump piston 13. This passage is open during the compression stroke so that air may flow from the cylinder into the fuel chamber as the piston 6 moves upward to thereby more effectively 70 secure the transfer of liquid fuel from said chamber 34 into the pump cylinder 12; while during the working stroke, particularly, and preferably until about the beginning of the next compression stroke this 75 passage is kept closed; the timing of the opening and closing of the passage being dependent upon the length of the cam 18, as will be appreciated. In four-stroke cycle engines the passage in question is preferably 80 kept closed during the exhaust and suction strokes, while in two-stroke cycle engines the passage should open at or about the end of the working stroke; the passage in question remaining open in both cases 85 during the compression stroke as hereinbefore explained.

Figure 1 shows the positions in which the parts are at or slightly before the beginning of the downward working stroke of the piston 6. During the preceding compression stroke the passage 40, 41 has remained open and air under constantly increasing pressure has flowed through said passage into the fuel chamber 34, and from said chamber 90 (carrying liquid fuel supplied to said chamber by the fuel measuring mechanism along with it) into the fuel pump chamber 12. At or slightly before, or slightly after the end of the compression stroke (according to whether an indicator card having a rapidly rising or a more nearly horizontal line indicating the burning of the fuel is desired) the fuel pump piston is moved quickly to the right by the operating mechanism hereinbefore explained; whereupon the passage 40 is cut off by movement of the recess 41 out of line therewith, the fuel and air within the fuel pump cylinder is further compressed and, finally, the valve 16 95 leaves its seat and the charge is forced into the working cylinder through the port 15. The tension of the spring 17 is preferably such that the heat developed during the compression of the fuel and air by the fuel pump piston (which is additional to the pressure produced during the compression stroke of the piston 6 as will be appreciated) is sufficient to ignite the charge, so that the same enters the engine cylinder 100 in a condition of incipient burning and finds therein the oxygen necessary to its complete combustion. The above action is secured if the spring in question is so adjusted as to secure a pressure of about 105 500

5 pounds per square inch within the fuel pump cylinder before the valve 16 opens; although our invention is obviously applicable to engines employing electrical or other forms of igniting devices, in which case the design of the parts may be such that a lower ultimate pressure is produced in the fuel pump cylinder.

10 The parts remain in the positions illustrated in Figure 1 at least throughout the greater part of the working stroke and, preferably, until shortly before the beginning of the next compression stroke of the engine. Before then, however, the fuel 15 pump piston moves to the left to secure a new supply of fuel to the fuel chamber 34, Figure 2 showing the positions of the parts soon after the beginning of such movement which is produced by the spring 22 after 20 the cam 18 ceases to hold the fuel pump piston in its right hand position.

As the fuel pump piston begins to move to the left the valve 16 closes the port 15, and as such movement continues the toe 27 25 swings to the right and pushes the plunger 28 of the fuel measuring mechanism in that direction. An elevated liquid fuel supply tank being contemplated it is obvious that the interior of the sleeve 29 will be full of 30 fuel, from which it follows that when the right hand end 36 of said plunger enters the measuring chamber 35 fuel will be forced therefrom through the port 33 and into the fuel supply chamber 34. At or 35 about this time the fuel pump piston will have reached its extreme left-hand position in which the recess 41 will register with the passage 40 and the engine piston 6 will be about to begin its compression stroke, 40 whereupon the fuel feeding operation hereinbefore traced will recur during the following compression stroke.

The fixed end of the lever 19 is shown 45 as adjustable so that the lever as a whole may be moved slightly transverse to the cam shaft, the effect of such movement being to vary the time at which the fuel is supplied to the working cylinder of the engine; movement of said fixed or pivoted end to the 50 right securing the operation of the pump and the supply of fuel slightly earlier in the cycle, while movement to the left has the effect of delaying such supply. In the form of our invention illustrated such adjustment is provided for by pivoting the lever upon an eccentric 20 which is carried by a shaft 42 supported in bearings in a housing 43, and which shaft may be angularly adjusted and held in proper position 55 by an arm 44 and slotted bracket or segment 45.

Having thus described and explained our invention, we claim and desire to secure by Letters Patent:

65 1. Fuel supplying mechanism for internal

combustion engines comprising a fuel supply pump operated by the engine and having a discharge port leading into the cylinder thereof; a fuel chamber communicating with said pump through a suitable port; means for supplying liquid fuel to said fuel chamber; an air supply passage leading from the cylinder of the engine into said fuel chamber; and means for controlling the flow of air through said passage.

2. Fuel supplying mechanism for internal combustion engines comprising a fuel supply pump operated by the engine and having a discharge port leading into the cylinder thereof; a fuel chamber communicating with said pump through a suitable port; means for supplying measured quantities of liquid fuel to said fuel chamber prior to each fuel supplying operation of said pump; an air supply passage leading from the cylinder of the engine into said fuel chamber; and means for controlling the flow of air through said passage.

3. Fuel supplying mechanism for internal combustion engines comprising a pump having a cylinder, a reciprocating piston operating therein, a discharge port leading from said cylinder into the cylinder of the engine, and a spring closed valve for controlling the flow of fuel through said port; a fuel chamber communicating with said pump cylinder through a suitable port; means operated in unison with said piston for supplying measured quantities of liquid fuel to said fuel chamber; an air supply passage leading from the cylinder of the engine into said fuel chamber; and means operated in unison with said piston for controlling the flow of air through said passage.

4. Fuel supplying mechanism for internal combustion engines comprising a pump having a cylinder, a reciprocating piston operating therein, a discharge port leading from said cylinder into the cylinder of the engine, and a spring closed valve for controlling the flow of fuel through said port; a fuel chamber communicating with said pump cylinder through a suitable port; means for supplying liquid fuel to said fuel chamber; an air supply passage leading from the cylinder of the engine into said fuel chamber; and means controlled by the piston of said pump for controlling the flow of air through said passage.

5. Fuel supplying mechanism for internal combustion engines comprising a fuel supply pump operated by the engine and having a discharge port leading into the cylinder thereof; a fuel chamber communicating with said pump through a suitable port; means for supplying liquid fuel to said fuel chamber; an air supply passage leading from the cylinder of the engine into said fuel chamber; means for controlling the flow of air through said passage; and a

valve adapted to remain closed until the pressure produced by said fuel supply pump exceeds the pressure within the cylinder of the engine at the end of the compression stroke for controlling the port aforesaid between said pump and the cylinder of the engine.

6. Fuel supply mechanism for internal combustion engines comprising a pump op-

- 10 erated in unison with the engine and having a cylinder, a reciprocating piston operating therein, and a discharge port leading from said cylinder into the cylinder of the engine; a fuel chamber communicating with said pump cylinder through a suitable port; means for supplying successive measured quantities of liquid fuel to said fuel chamber; an air supply passage leading from the cylinder of the engine into said fuel chamber and through which air may flow during the compression stroke of the piston of the engine; means for closing said passage when the piston of the engine is adjacent the end of its compression stroke; and a spring 20 closed valve for controlling the port aforesaid between said pump and engine cylinder.

7. Fuel supplying mechanism for internal combustion engines comprising a pump op-

- 30 erated in unison with the engine and having a cylinder, a reciprocating piston operating therein, and a discharge port leading from said cylinder into the cylinder of the engine; a fuel chamber communicating with said pump cylinder through a suitable port; means for supplying successive measured quantities of liquid fuel to said fuel chamber; an air supply passage leading from the cylinder of the engine into said fuel chamber and through which air may flow during the compression stroke of the piston of the engine; means for closing said passage when the piston of the engine is adjacent the end of its compression stroke; a 40 valve for controlling the port aforesaid between said pump and engine cylinders; and means whereby said valve is permitted to open only when the pressure within said pump cylinder exceeds the pressure produced in the engine cylinder at the end of the compression stroke of the engine piston.

8. Fuel supplying mechanism for internal combustion engines comprising a pump op-

- 55 erated in unison with the engine and having a cylinder, a reciprocating piston operating therein, and a discharge port leading from said cylinder into the cylinder of the engine; a fuel chamber communicating with said pump cylinder through a port which is overrun by the pump piston during the fuel supplying stroke thereof; means for supplying successive measured quantities of liquid fuel to said fuel chamber; an air supply passage leading from the cylinder of the engine into said fuel chamber and

through which air may flow during the compression stroke of the piston of the engine, and which air passage includes a recess in the pump piston adapted to register therewith during said compression stroke, and to be out of registry therewith at other times; and a spring closed valve for controlling the port aforesaid between said pump and engine cylinders.

9. Fuel supplying mechanism for internal 75

combustion engines comprising a pump operated in unison with the engine and having a cylinder, a reciprocating piston operating therein, and a discharge port leading from said cylinder into the cylinder of the engine; a fuel chamber communicating with said pump cylinder through a port which is overrun by the pump piston during the fuel supplying stroke thereof; means for supplying successive measured 80 quantities of liquid fuel to said fuel chamber; an air supply passage leading from the cylinder of the engine into said fuel chamber and through which air may flow during the compression stroke of the piston of the engine, and which air passage includes a recess in the pump piston adapted to register therewith during said compression stroke, and to be out of registry therewith at other 85 times; a valve for controlling the port aforesaid between said pump and engine; and means whereby said valve is permitted to open only when the pressure within said pump cylinder exceeds the pressure produced in the engine cylinder at the end of the compression stroke of the engine.

10. Fuel supplying mechanism for internal combustion engines comprising a fuel supply pump operated by the engine and having a discharge port leading into the cylinder thereof; means for supplying liquid fuel to said pump; an air supply passage leading from the cylinder of the engine and through which air is supplied to said pump; means for closing said passage during the fuel supplying operation of said fuel pump; and a valve so arranged as to open when the pressure produced by said pump exceeds the pressure within the engine cylinder for controlling the discharge port aforesaid of said fuel supply pump.

11. Fuel supplying mechanism for internal combustion engines comprising a fuel supply pump operated by and in unison with the engine and having a discharge port leading into the cylinder thereof; means for supplying measured quantities of liquid fuel to said pump; an air supply passage leading from the cylinder of the engine and through which air is supplied to said pump; means for closing said passage during the fuel supplying operation of the said fuel pump; and a valve for controlling the discharge port aforesaid adapted to open only when the pressure produced by said fuel pump

exceeds the pressure within the engine cylinder at the end of the compression stroke.

12. Fuel supplying mechanism for internal combustion engines comprising a fuel supply pump operated by and in unison with the engine and having a discharge port leading into the cylinder thereof; means for supplying measured quantities of liquid fuel to said pump; an air supply passage leading from the cylinder of the engine and through which air is supplied to said pump; means for closing said passage during the fuel supplying operation of said fuel pump; and a spring pressed valve for controlling the port aforesaid between said fuel pump and engine cylinder and which valve is adapted to open only when the temperature of the air and fuel compressed by said fuel pump is sufficient to cause the burning of the liquid fuel as it enters the engine cylinder.

13. Fuel supplying mechanism for internal combustion engines comprising a fuel supply pump operated by and in unison with the engine and having a cylinder, a piston reciprocating therein, and a discharge port leading into the engine cylinder; means for supplying measured quantities of liquid fuel to said pump cylinder; an air supply passage leading from the cylinder of the engine and through which air is supplied to said pump cylinder, and which passage is controlled by a recess provided in said fuel pump piston adapted to register with and to be out of line with said air supply passage; and a spring closed valve for controlling the port aforesaid between said fuel pump and engine cylinders and which valve is adapted to open only when the pressure within the fuel pump cylinder exceeds the pressure in the engine cylinder at the end of the compression stroke of the engine piston.

14. Fuel supplying mechanism for internal combustion engines comprising a fuel supply pump operated by and in unison with the engine and having a cylinder, a piston reciprocating therein, a discharge port leading from the fuel pump cylinder into the engine cylinder, and a spring closed valve operable by pressure within the pump cylinder for controlling said port; a fuel chamber communicating with said fuel pump cylinder through a suitable port; a fuel measuring device operated by the operating means for said fuel pump and adapted to supply measured quantities of liquid fuel to said fuel chamber; an air supply passage leading from the cylinder of the engine into said fuel chamber; and means for closing said air supply passage during the fuel supplying operation of said fuel pump.

15. Fuel supplying mechanism for internal combustion engines comprising a fuel supply pump having a cylinder, a piston

reciprocating therein, a discharge port leading from the fuel pump cylinder into the engine cylinder, and a valve for controlling said port; a fuel chamber communicating with said fuel pump cylinder through a suitable port; an air supply passage leading from the cylinder of the engine into said fuel chamber; means for closing said air supply passage during the fuel supplying operation of the fuel pump; toggle mechanism whereby said fuel pump piston is operated; and a reciprocating fuel measuring device operated by said toggle mechanism and adapted to supply measured quantities of liquid fuel to said fuel chamber.

16. Fuel supplying mechanism for internal combustion engines comprising a fuel supply pump having a cylinder, a piston reciprocating therein, a discharge port leading from the fuel pump cylinder into the engine cylinder, and a valve for controlling said port; a fuel chamber communicating with said fuel pump cylinder through a suitable port; an air supply passage leading from the cylinder of the engine into said fuel chamber; means for closing said air supply passage during the fuel supplying operation of the fuel pump; an adjustable sleeve having an internal measuring chamber to which liquid fuel is supplied, and an outlet port leading into said fuel chamber; a reciprocating plunger operating within said sleeve and the extremity of which enters said measuring chamber; and means for simultaneously operating said fuel pump piston and said plunger.

17. Fuel supplying mechanism for internal combustion engines comprising a fuel supply pump having a cylinder, a piston reciprocating therein, a discharge port leading from the fuel pump cylinder into the engine cylinder, and a valve for controlling said port; a fuel chamber communicating with said fuel pump cylinder through a suitable port; an air supply passage leading from the cylinder of the engine into said fuel chamber; means for closing said air supply passage during the fuel supplying operation of the fuel pump; toggle mechanism whereby said fuel pump piston is operated; a reciprocating plunger operated in one direction by said toggle mechanism, and in the other direction by a spring acting thereupon; a longitudinally adjustable sleeve within which said plunger operates, and which sleeve has an internal measuring chamber to which liquid fuel is supplied, and into which the end of said plunger enters to force measured quantities of fuel therefrom and into said fuel chamber.

18. Fuel supplying mechanism for internal combustion engines comprising a fuel supply pump; a fuel chamber communicating with said pump through a suitable port; means for operating said fuel supply

pump; a reciprocating plunger operated by said pump operating means; and a longitudinally adjustable sleeve within which said plunger operates, and which sleeve has an internal measuring chamber to which liquid fuel is supplied, and into which the end of said plunger enters to force measured

quantities of fuel therefrom and into said fuel chamber.

In testimony whereof we affix our signatures.

CHARLES R. SHORT.
ALEX TAUB.
